FIG-2-

INVENTOR
X. D. Johnson,
By Ann Ann Crampton,
his atty.

UNITED STATES PATENT OFFICE.

X A D. JOHNSON, OF TOLEDO, OHIO.

SCRAPING TOOL.

1,402,163.

Specification of Letters Patent. Patented Jan. 3, 1922.

Application filed December 20, 1920. Serial No. 431,830.

To all whom it may concern:

Be it known that I, X A D. JOHNSON, a citizen of the United States, and a resident of Toledo, in the county of Lucas and State of Ohio, have made an Invention Appertaining to Scraping Tools; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to a tool for scraping cylindrical surfaces, and particularly for use in scraping the inner walls of engine cylinders.

The interior side walls of engine cylinders frequently become scored from one cause or another and the scorings are then filled with metal. After filling the scorings it is necessary to dress down or scrape away the surface metal to provide the wall with a perfectly smooth cylindrical surface.

The primary object of my invention is the provision of a simple and efficient tool for use particularly in scraping or dressing down the filled surface of engine surfaces to correct cylindrical form, and which is easily and quickly adjustable to operate on cylinders of different diameters. Further objects and advantages of the invention will be apparent from the following detailed description thereof.

While the invention, in its broader aspect, is capable of embodiment in numerous forms, a preferred embodiment thereof is illustrated in the accompanying drawings, in which—

Fig. 1 is a side view of a tool embodying the invention with parts broken away. Fig. 2 is an end view thereof in scraping engagement with a cylinder, and Fig. 3 is a face view of a scraper knife used in connection with the tool.

Referring to the drawings, 1 and 2 designate the two cooperating members of a clamping head for releasably carrying a scraper knife or blade 3 therebetween with its scraping edge projecting therefrom. The member 2 is carried by a sleeve or hollow stem 4 projecting from the outer face thereof, preferably at right angles thereto, and the member 1 is in threaded engagement

with the outer end of a stem or rod 5, which projects from a handle 6 forwardly through the sleeve 4 and member 2 into the member 1. The stem 5 has a shoulder 7 in engagement with the outer end of the sleeve 4 to limit the movement of the stem therein during a threading of the stem to the member 1, whereby a threading of the stem in one direction into the member 1 will cause it to have clamping engagement with the blade 3 in opposition to the member 2.

One of the clamping members, 1 in the present instance, has a lug 8 projecting therefrom at its upper edge toward the other member for coaction therewith to prevent a tilting of the member 1 by reason of its clamping engagement with the blade 3 at the opposite side of the head axis. One of the members, 2 in the present instance, also has a pair of studs 9 projecting therefrom through registering apertures in the member 1 to prevent a relative turning of the clamping members. The edges of the clamping members from which the blade 3 projects are preferably, but not necessarily given a slight convex curve longitudinally thereof, and one member, the member 2 in the present instance, is provided at each end with guide lugs 10, which lugs are intended to slide on the cylindrical surface being operated on to limit the depth of cut of the blade which is carried by the clamping head between the two guide lugs 10.

The blade 3 is preferably shorter than the space between the guide lugs 10 and has its scraping surface curved in convex form with the radius of the curvature preferably less than the radius of a cylinder on which the tool is to operate, as shown. The blade may be freely removed from between the clamping members upon a loosening of the same, or may be set in any position of adjustment relative thereto as desired. The upper or inner edge of the blade 3 is recessed to adapt it to fit around the stem 5.

In the use of my tool the blade is properly adjusted to suit the bore of the cylinder on which it is to operate by placing the tool in a true cylinder of the size desired with the lugs 10 in contact with the wall thereof and with the blade 3 free to adjust itself to the cylinder so that a perfect three point contact is had between the tool and cylinder wall. The clamping head is then tightened to firmly hold the blade in the adjusted position by a

turning of the handle 6 relative to the stem 4. The tool may now be used for scraping a cylinder of the size for which adjusted, the scraping being accomplished by a reciprocating movement of the tool longitudinally of the handle. During the scraping operation the gauge points 10 will straddle the filling or other rough part to be scraped which is operated on by the knife blade, the knife continuing to act thereon until the cylinder surface is brought into true cylindrical form, it then being impossible to further scrape the cylinder surface due to the depth limiting contact of the gauge points 10 therewith.

15 I wish it understood that my invention is not limited to any specific construction, arrangement or form of the parts as it is capable of numerous modifications and changes without departing from the spirit of the 20 claims.

Having thus described my invention, what I claim as new and desire to secure by Letters Patent, is,—

1. A tool for scraping protuberant portions from a circular surface, comprising a clamping head having spaced guide projections for contact with the surface acted on, the spacing of the projections being transverse to the surface axis, and a thin blade-like scraping member rigidly clamped by the head between the projections.

2. A tool for scraping protuberant portions from a cylindrical surface, comprising a clamping head having guide projections spaced transversely to the axis of the surface acted on, and a thin blade-like scraping member rigidly clamped by the head between the projections and cooperating therewith to form a three-point contact with the surface acted on, the scraping member having its scraping edge describing a curve which is of less radius than the curvature of the surface acted on.

3. A tool of the class described, having a handle, a clamping head at an end of the handle, and a substantially flat blade-like scraping member rigidly clamped by the head with its scraping edge transverse to the handle axis, the clamping head having 45 guide lugs at opposite ends of the scraping

member and cooperating therewith to form a three-point contact with the surface acted on, the contact points describing a curve corresponding to the desired curvature of such surface.

4. A tool of the class described comprising a clamping head, a handle projecting from the head, a scraping blade carried by the head with its scraping edge transverse to the handle, said head having guide lugs 55 at opposite ends of the blade, which cooperate therewith to form a circular three-point contact of predetermined diameter.

5. A tool of the class described, comprising a clamping head having guide lugs projecting therefrom for coaction with the surface to be scraped, and a blade carried by the head intermediate the guide lugs and cooperating therewith to form a three point surface contact for the tool the ends of the 60 blades being adjacent to the lugs.

6. A tool of the class described comprising a clamping head having relatively movable clamping members, and a blade adjustably carried by the head and having a longitudinally convexed scraping edge projecting from the head, the head having guide projections at opposite ends of the blade to cooperate with the blade to form a three point contact for engagement with the surface to 75 be scraped.

7. A tool of the class described, comprising two clamping members forming a clamping head, one member having a hollow stem projecting therefrom, a handle shouldered 85 against an end of the stem and having a part projecting through the stem and its member and threaded into the other member and adjustable to impart blade clamping and releasing movements to the members, and a 90 blade clamped between the members and having a longitudinally convexed scraping edge projecting from the members, one of the members having guide lugs projecting therefrom and cooperating with the blade to 95 form a multiple point contact with a curved surface to be scraped.

In testimony whereof I have hereunto signed my name to this specification.

X A. D. JOHNSON.
